UNITED STATES PATENT OFFICE.

IVAN ANDERSON, OF SACRAMENTO, CALIFORNIA.

MUSIC STAND.

Application filed April 13, 1925. Serial No. 22,922.

This invention relates to improvements in devices for supporting music being played, and especially to stands such as are used by musicians in orchestras, bands and similar organizations.

Written music is now almost entirely in the form of books or leaflets, which rest on the stand and must be turned by hand. The musician must therefore remove one hand from his instrument in order to turn the page, which is frequently necessary at a poor moment destroying momentarily the continuity of his playing. In the case of a leaflet the same is liable to slip or blow off the stand and the page of a book frequently refuses to stay turned. Such happenings, which very often occur, make for confusion and lack of proper harmonious rendering of the piece being played.

The principal object of my invention therefore is to eliminate the above deficiencies in the necessary moving of the music by arranging the music in roll instead of sheet or book form, and providing a stand in which the roll is removably mounted with means for enabling said roll to be turned to expose an unplayed portion by the foot of the musician. The player is therefore able to retain the use of both hands in manipulating his instrument. Further the possibility of the music falling off the stand or being otherwise moved out of place is also eliminated.

The control means is so arranged that it does not interfere with the desired adjustment of the stand both vertically and angularly, as is necessary to suit the needs of different users.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective view of the stand as in readiness for use.

Fig. 2 is a sectional end view of the roll

holding box taken on a plane mainly just inside one of the ends thereof.

Fig. 3 is a fragmentary end section view 55 showing the direction controlling pawl and ratchet mechanism.

Fig. 4 is a sectional plan on the line 4—4 of Fig. 2.

Fig. 5 is a fragmentary vertical section on 60 the line 5—5 of Fig. 2.

Fig. 6 is a fragmentary side view partly in section of the lower end of the stand pedestal showing the pedal structure.

Fig. 7 is a fragmentary vertical section on 65 the line 7—7 of Fig. 4.

Referring now more particularly to the characters of reference on the drawings, the numeral 1 denotes a tubular pedestal supported by suitable outwardly projecting legs 70 2, mounted in a manner common to such stands. Slidably and turnable in the pedestal is a tubular stem 3 held in any desired position by a thumb screw 4, as shown in Fig. 1. The upper end of the stem 3 is pivotally 75 secured to brackets 5 by horizontal clamping bolts 6, the brackets being mounted on the back of a rectangular casing 7 which is open in front.

Removably mounted in the casing at the 80 top and bottom and adjacent the front thereof are spools 8 and 9 respectively, these spools being about the size and general form of those used in connection with player piano rolls. The lower spool 9 is mounted on 85 spindles 10 and 11. The spindle 10 is longitudinally immovable in the casing and its inner end is square or otherwise shaped to engage the spool in removable driving relation, so that when the spindle is turned the 90 spool will turn also. To enable the spindle to be turned its end outwardly of the casing is provided with a suitable button or handle 12.

The other spindle 11 is mounted in connection with a spring 13 on the outside of the casing which acts to hold the inner end of the spindle seated in the adjacent end of the spool. The spindle 11 has a handle 14 on its outer end so that it may be drawn clear of the spool, as shown in dotted lines in Fig. 5, thus permitting the spool to be also disengaged from the spindle 10 and removed 100 from the casing.

The upper spool 8 is also mounted on two spindles 15 and 16 corresponding in function to the spindles 10 and 11. The spindle 16 is identical in form, mounting and operation as the spindle 11, having a spring 13^a of the same form. The spindle 15 however is of special construction and arrangement, as will be hereinafter seen.

The spindle 15 has a pinion 17 mounted in driving relation therewith, which pinion meshes with a gear 18 turnably mounted on a fixed shaft 19 which in turn is mounted in the casing behind the spool 8. Turnable on the shaft 19 in spaced relation thereto is a sleeve 20. A coil spring 21 is disposed about the shaft between the same and the sleeve, one end of said spring being fixed to the sleeve and the other end to the shaft. The latter being immovable, the spring of course tends to rotate the sleeve when the spring is wound up.

Mounted in connection with the sleeve is a spring pressed dog 22 normally engaging a ratchet wheel 23 which is fixed onto the gear 18.

Wrapped around the sleeve 20 for a certain number of turns centrally of the length thereof is a flexible cord or wire 25 which then projects down past a direction changing roll 26 in the casing, over a guide and direction changing sheave 27 mounted adjacent the pivots 6, down through the stem 3 and pedestal 1, around a guide sheave 28 at the bottom of said pedestal, and then upwardly to a connection with the inner end of a pedestal arm 29. This arm has a foot pad 30 on its outer end and is mounted on a cross bar 31 extending between two of the legs 2. The inner end of the arm 29 moves in a vertical and curved guide 32 fixed on the pedestal. In order to be able to limit the upward movement of the pedestal arm if desired the sides of the guide have vertically spaced holes 33, through which a cross pin may be placed. The downward movement of the arm is limited by a fixed stop 34 of suitable character.

The music used in connection with my stand is in the form of a continuous roll 35 normally wound on the lower spool 9 and adapted to be unwound therefrom onto the take-up spool 8. The latter has suitable means for attaching the end of the roll thereto, such for instance as is commonly employed in connection with player piano rolls and the like.

The parts of the operating mechanism are so arranged that when the pedestal is depressed the wire 25 will be unwound from the sleeve 20 which rotates the same. The spring 21 will become wound up, the dog will rotate the ratchet and gear and the latter through the pinion 17 will cause the rotation of the spool 8 in a direction such that the music roll 35 extending between the

spools will move upwardly. Also the relative proportion of the parts is such that a complete depression of the pedal causes the music roll to move the entire distance between the spools, though this can of course be varied by varying the amount the pedal is moving.

When the pressure is removed from the pedal the spring 21 tends to unwind, causing the rotation of the sleeve 20, the winding of the wire 25 thereon, and restoring the pedal to its original position. At the same time no rotation of the spool 8 takes place since the dog 22 then backs around the ratchet 23 without turning the same and of course without turning the gear which controls the turning of the pinion 17.

When it is desired to rewind the music on the spool 9 said spool is turned by turning the handle 12. At such time it is of course not desired to have the sleeve 20 turn so some means must be provided to prevent this without interfering with the necessary backward rotation of the spool 8.

If the dog 22 was raised from the ratchet wheel this of course would serve the purpose but this dog is practically concealed, is hard to get at and does not occupy any fixed location relative to the casing. It cannot therefore be provided with releasable means operable from outside the casing.

I have therefore arranged for the driving connection of the pinion 17 with the spool 8 to be broken when desired, so that the spool may rotate backwards, enabling the music roll to be wound on the spool 9 without turning the gearing or the sleeve 20.

The spindle 15 and associated parts are therefore constructed as follows:

Adjacent but spaced from its inner end 105 the spindle 15 has a short rectangular portion 15^a adapted to fit a correspondingly shaped socket in the end of the spool 8. The round portion of said spindle at the inner end thereof beyond the portion 15^a is longer 110 than the latter and fits a round socket in the spool. The spindle 15 is slidable in its bearing 36 and is provided on its outer end with a handle 15^b.

The pinion 17 is feather-keyed onto the 115 spindle so that the latter can move longitudinally without moving the pinion. It will therefore be seen that if the spindle 15 is drawn out the portion 15^a thereof may be removed from its socket in the spool 120 without entirely withdrawing the portion of the spindle beyond the part 15^a from said spool. The spindle may therefore freely turn and at the same time is maintained supported at both ends.

The pinion and spool are held from longitudinal movement, and the spindle 15 limited in its outward movement by a bracket 37 mounted on the casing. This bracket projects between the spool and pin without 130

interfering with the necessary outward movement of the portion 15^a of the spindle. All these features are fully shown in Fig. 7.

If it is desired to rotate the spool 8 by hand in the same direction as that imparted thereto by depression of the pedal, this can of course be done by turning the handle 15^b without pulling the spindle 15 out, since with such operation the ratchet 23 will move ahead of the dog without imparting movement to the sleeve 20. A swivelled stop or latch 38 is placed to normally engage handle 15^b and prevent outward movement of spindle 15.

The casing may be swiveled on its pivot 6 to set the same at different angles without interfering with the operation of the wire or causing the same to bind, owing to the guide sheave 27 being located adjacent the pivots 6.

Also vertical adjustment of the stem can be had without necessitating any adjustment to the wire being made, since the spring 21 is of ample extent to wind or unwind, to take up or let out the wire the necessary amount from the sleeve 20 without interfering with the further operation of the spring when the pedal is depressed.

The end cuts or sockets in both spools 8 and 9 are preferably of the same form, so that the spools can be interchanged if desired.

I may also associate a dog and ratchet mechanism 39 with handle 12 if desired, so as to enable the music roll to be maintained taut between the spools.

The device may also be installed, with certain necessary rearrangement of parts, on pianos and organs.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A music stand including a pedestal, a stem slidably mounted therein for vertical adjustment, a casing supported by the stem and arranged for swivel movement relative thereto in a vertical plane, music-roll supporting spools mounted in spaced relation in the casing, a mechanism for rotating one of the spools including an operating pedal mounted in a fixed position on the pedestal, and means whereby said mechanism may

function without adjustment or interference regardless of the adjustment of the stem in the pedestal and of the casing on the stem.

2. A music stand including a pedestal, a casing mounted thereon, vertically spaced spools in the casing, opposed spindles for the spools mounted in the casing, one spindle of one of the spools having driving engagement with its spool, a pinion mounted in driving relation on said spindle, a gear meshing with the pinion, a pedal mounted on the pedestal, a sleeve mounted concentric with but independent of the gear, a flexible element from the pedal wound about the sleeve and unwinding therefrom and rotating the sleeve with the depression of the pedal, a pawl and ratchet mechanism between the sleeve and gear acting to cause the latter to rotate with the sleeve only when the element is being unwound from the latter, and spring means acting to rotate the sleeve to rewind the element thereon when the pressure on the pedal is released.

3. A music stand including a pedestal, a casing mounted thereon, vertically spaced spools in the casing, opposed spindles for the spools mounted in the casing, one spindle of one of the spools being turnably mounted at its inner end in the adjacent end of the spool, a cross member on the spindle outwardly of such end, and normally fitting a socket in the spool whereby to maintain the spool and spindle in driving relation, bearing means for the spindle to allow the same to have limited sliding movement relative to the spindle to remove the cross member from the socket while maintaining the portion of the spindle beyond said cross member in engagement with the spool, a pinion splined in the spindle and held against sliding movement therewith, foot actuated means for rotating the pinion, and handle means on the spindle outwardly of the casing.

4. A structure as in claim 1, in which said means includes a vertically movable and flexible member connected to the pedal and extending upwardly inside the pedestal and stem centrally thereof, a rotatable member mounted in the casing and about which the flexible member is wound, driving means between said rotatable member and one of the roll spools, and a coil spring connected to said rotatable member and tending to rotate the same in one direction; the operative length of the spring being sufficient to take up or let out the vertical member when the pedal and stem are relatively adjusted as to length, without interfering with the subsequent functioning of the spring.

In testimony whereof I affix my signature,
IVAN ANDERSON.
